UNITED STATES PATENT OFFICE.

CLAUD E. FULLER, OF NEW YORK, N. Y., ASSIGNOR TO NEW YORK BRICK HANDLING CORPORATION, OF NEW YORK, N. Y., A CORPORATION OF NEW YORK.

KILN BOTTOM AND METHOD OF BUILDING KILNS.

Application filed January 25, 1928. Serial No. 249,277.

My present invention relates to the manufacture of brick, and more particularly to an improved form of kiln bottom and to the method of building kilns.

In burning brick, one of the principal forms of kilns employed is the so-called scoved kiln and heretofore it has always been the practice to build the arches of such kiln extending through from one side to the other. As an improvement in the art of building kilns there has lately come into practice the use of the so-called permanent kiln bottoms, and in the development of such kiln bottoms it has been an invariable practice to date to build the arches extending from one side of the kiln to the other. In the so-called scoved kiln it has always been difficult to get the middle portion of the kiln heated to the proper degree, this being particularly the case where oil burners have been used as a heating medium. This failure to heat the middle portion of the kiln is caused to a great extent by the fact that the oil burners throw their flame in from each side of the line and such flames meet approximately at the middle of the kiln, having a tendency to form a dead space with the consequence that there is a black spot left in the arch for a considerable period of time. Various steps have been taken to obviate the appearance of the black spot in the middle of the kiln, one of the most successful being to reduce the pressure on one of the burners on any arch and to increase the pressure of the burner on the opposite side, and in this way the flame from the burner whose pressure is increased will extend beyond the middle portion of the kiln and will heat up such portion and remove the black spot therefrom. This procedure of course necessitates extra time as well as extra fuel and is objectionable.

In my present invention I have devised means for overcoming the difficulties enumerated above, and in carrying out my invention, I have provided a permanent kiln bottom—although the invention is applicable to kilns not employing a permanent kiln bottom—and arrange the fire boxes in staggered relation, with each fire box of a length to extend for a predetermined distance beyond the middle of the kiln, with the result that there are no opposing flames in the fire boxes and the heat from the flame heats up the middle

portions of the kiln and totally prevents the appearance of the black spot.

The principal object of my invention, therefore, is an improved kiln structure.

Another object of my invention is an improved method of building kilns.

Other objects and novel features of the construction and arrangement of parts comprising the apparatus will appear as the description of the invention progresses.

In the accompanying drawings,

Fig. 1 is a plan view of a portion of a kiln to which my invention has been applied;

Fig. 2 is an end elevation of a structure similar to Fig. 1 but with the bricks hacked in position thereon;

Fig. 3 is a central sectional elevation of a kiln embodying the structure shown in Figs. 1 and 2 and with portable scoving in position thereon;

Fig. 4 is a sectional elevation on the line 75 4—4 of Fig. 1;

Fig. 5 is a section on the line 5—5 of Fig. 1;

Fig. 6 is a sectional elevation on the line 80 6—6 of Fig. 1, and

Fig. 7 is a perspective view of a pre-formed element utilized in building up a kiln bottom shown in the figures.

Referring to the drawings, there is shown a permanent form of kiln bottom designated 85 generally in Fig. 1 by the numeral 10, such kiln bottom being made up of common brick 11, fire brick 12, and arch forms 13, the arch forms being of the shape shown in Fig. 7, where it will be seen that each form is provided with a pair of members 14 and 15 respectively, extending outward from one side of the form 13 and insuring that when a second form 13 is placed in position thereagainst that a flue or passageway will exist between 90 adjacent forms 13. In building the permanent kiln bottom piers composed of fire brick 12 are arranged parallel to each other to define a passageway 16 therebetween, such fire brick piers 12 extending inward from the side toward the middle of the arch a sufficient distance to insure that the most intense heat from the firing material engages with the fire brick. These piers are then continued inwardly, using common brick 11, and such common brick 11 in the shape of piers extend inwardly a predetermined distance 100 beyond the center line 17—17 of the kiln.

The remaining width of the kiln bottom 10 is then built solidly with common brick 11, as clearly shown in Figs. 3 and 4. On top of the piers formed of the fire brick 12 and 5 common brick 11 and spanning a space 16 are placed the predetermined forms 13, preferably of fire brick or equivalent substance. Such predetermined forms 13 are built over the space 16 to define an arched passageway 10 extending from one side of the kiln as far as the pier structure continues and the common brick 11 built solidly across the passageway 16 extends upwardly to a height equal to the height of the piers and predetermined forms 15 13. Along each side of the kiln bottom there is arranged a course of fire brick 12 lower than the course of such fire brick of which the piers above described are formed and on top of such lower courses is placed 20 the predetermined forms 13, this not only providing an opening for the arch 16, but also providing a shelf on which may rest the portable scoving 18 employed in connection with the kiln.

25 By referring to Fig. 1 it will be noted that the arch structures of which the predetermined forms 13 form the top, extend beyond the center line 17 of the kiln bottom and that such arches 16 are arranged in staggered relation to each other. Therefore, although when a heating flame, as the flame from burning oil, is projected into the arches 16, while there may be a dead space at the inner end of each arch, yet such dead space 30 will have adjacent to it on either side thereof a wall which is being subjected to an intense heat and, therefore, with this construction, the inner or middle portion of the kiln is subjected to as much heat as any 35 of the outlying portions thereof, and by such means, therefore, I have been able to absolutely eliminate the cold area that formerly existed in prior structures.

40 After the kiln bottom above described is built, there is built thereon a kiln formed of unit stacks of brick 20, each of the lower courses in the first stacks being provided with finger courses 21, the spaces between such finger courses not only providing a 45 space in which lifting forks may be placed, but also such spaces are brought into alignment with the spaces between adjacent predetermined forms 13 and act, therefore, as flues and through which the heat from the

furnace in the arches 16 pass upward into 55 the bricks. Before burning and after the unit stacks of brick 20 are in position, it is usual to place mortar 22 around the outer side of the kiln and on the ledges formed of the two outer courses of predetermined forms 13 and in such mortar rests the lower end of the portable scoving 18.

With my above construction, I am enabled to secure a zone through the middle of the kiln which has approximately double the 60 heating area of present types of kilns and this without the use of any additional burners. The novel feature of staggering the arches in the up-draft kiln is broadly new 65 as far as I am aware and I desire to claim 70 the same broadly.

Having thus described my invention, what I claim as new is:

1. In a structure of the kind described, the combination of a plurality of arches 75 each of less length than the width of the structure and extending inwardly from either side thereof.

2. In a structure of the kind described, the combination of a plurality of arches arranged side by side and in staggered relation to each other. 80

3. In an improved kiln structure the combination of a plurality of arches arranged side by side and in staggered relation to 85 each other and each alternate arch extending from the same side of the kiln and to a point beyond the middle thereof.

4. In an improved kiln, the combination of a kiln bottom, a plurality of arches 90 formed therein, said arches being of less length than the width of the kiln, and arranged in staggered relation with respect to each other, each alternate arch extending through the kiln from opposite sides, whereby the heating will extend beyond the middle of the kiln and the dead spot eliminated. 95

5. That improved method of building kilns which consists in arranging the arches to allow the heating flame utilized in burning the kiln to pass beyond the center of the kiln in each arch without encountering an opposing flame from the opposite side thereof. 100

In testimony whereof, I have signed my 105 name to this specification.

CLAUD E. FULLER.
